DISPLAY STAND FOR SHIRTS OR THE LIKE

Daniel E. Gelles, 115 Ocean Ave., New York, N.Y.

Filed Mar. 15, 1963, Ser. No. 73,990

Term of patent 14 years

(Cl. D80—9)

I claim:

The ornamental design for a display stand for shirts or the like, substantially as shown and described.
